PACKAGING TRAY FOR FOOD

Donald C. Rowe, Box 231, La Conner, Wash.

Filed Apr. 26, 1963, Ser. No. 74,636

Term of patent 14 years

(Cl. D58—13)

Fig. 1.

Fig. 2

*Fig. 3.**Fig. 4.**Fig. 5.*

FIG. 1 is a top perspective view of a packaging tray for food showing my new design;

FIG. 2 is a bottom plan view thereof;

FIG. 3 is a side elevational view, the opposite side being a mirror image thereof;

FIG. 4 is an end elevational view thereof taken from the left of FIG. 2; and

FIG. 5 is an end elevational view taken from the right of FIG. 2.

I claim:

The ornamental design for a packaging tray for food, as shown and described.
